FOLDING RULE

Gustav J. T. Neuberg, Chicago, Ill.

Application July 18, 1931, Serial No. 551,695

1 Claim. (Cl. 33—111)

This invention relates generally to folding rules consisting of a plurality of sections that are pivotally connected together, the object being to provide a rule of this character which is made up in sections of exactly six inches long, each section being provided with a square cut end for facilitating in the use of the said rule.

In folding rules heretofore used, the sections comprising the same are not of any fixed definite length and the ends thereof are generally rounded, with the result that in the event the rule is injured or broken intermediate the ends thereof the whole rule is no longer capable of exact use and must therefore be discarded or thrown away. In my improved rule, however, by providing each section of a definite length, any injury or breakage of the rule intermediate the ends thereof will not destroy the utility of the rule, as the same may be severed at the next adjacent pivotal connection, thereby leaving a workable rule which would still be made up of equal six inch sections.

It is therefore the main object of this invention to provide a folding rule of the character described, which is made up of a plurality of pivotally connected sections, each section being of a six inch length, the six inch mark terminating at the squared off end of said section. Thus, if a four foot rule is provided, the same will be made up of eight six inch sections and in the event that the said rule should be broken, say at the 38" mark, the last two sections of said rule may be readily removed, thereby leaving a folding rule of exactly 36" long, while rule will be in as good a working condition and as efficient in use as the original rule, only that the same would be of a three foot length instead of the original four foot length.

Another object of this invention is to provide a rule of the character described, which is provided with the usual markings at the inch spaces thereof, said markings extending from one to forty-eight in a four foot rule, and in addition to the above markings there are also provided markings of one to twelve for each of the intermediate one foot sections thereof, whereby the efficiency and use of the rule will be greatly facilitated.

A still further object of this invention is to provide a folding rule of the character described, which is made up of equal sections, the ends of which are cut square, whereby the same may be disposed against a square end of the object to be measured for facilitating in taking the measurement of said object.

With the foregoing and other objects in view, which will appear as the description proceeds, the invention consists in certain novel features of construction, arrangements and combination of parts, hereinafter more fully described, illus-

trated in the accompanying drawing and particularly pointed out in the appended claim, it being understood that various changes in the form, proportion, size and minor details of the structure may be made without departing from the spirit or sacrificing any of the advantages of the invention.

For the purpose of facilitating an understanding of my invention I have illustrated in the accompanying drawing a preferred embodiment thereof, from an inspection of which, when considered in connection with the following description, my invention, its mode of construction and assembly and many of its advantages should be readily understood and appreciated.

Referring to the drawing in which the same characters of reference are employed to indicate corresponding or similar parts throughout the several figures of the drawing:

Figure 1 is a side view of a ruler constructed in accordance with this invention showing my improved markings thereon;

Figure 2 is an enlarged fragmental portion of the rule showing it about actual size and also showing the markings thereon as they appear at the beginning and at the end of said rule; and

Figure 3 is a diagrammatic view showing my improved rules as applied to an object to be measured.

In the preferred embodiment illustrated in the drawing the numeral 10 designates generally my improved folding ruler which is made up of a plurality of equal sections 11, and the end section 12 which is shorter in length than the other sections, said end section being exactly six inches long. Each of said sections is provided with cross lines 13 that separate the rules into inch lengths, sections or spaces that are numbered from one to forty-eight inclusive as in ordinary linear measurement. In addition to the cross lines 13 there are also provided the usual shorter lines 14 that divide the inch space into fractions of an inch as is common and well known in an ordinary ruler.

As illustrated more clearly in the drawing, the section 12 is pivotally connected to its adjacent section 11 at one end thereof, said connection being of such arrangement that when said section 12 is swung to the left, as viewed in Figure 1, to bring the same into alignment with its adjacent section 11, the said two sections will form a rule exactly twelve inches long.

The cross line 15, which marks the end of the sixth one-inch space is also the end of the first section 12, said end being cut square so as to exactly coincide with the cross line 15. Similarly, the cross line 16, which marks the end of the twelfth inch space, coincides with the square cut end of the second section. In a similar manner the reference numeral 17 designates

the cross line of the eighteenth inch space, as well as the square cut end of the third six-inch section; the reference numeral 18 designates the cross line of the twenty-fourth inch space as well as the square cut end of the fourth six-inch section; the reference numeral 19 designates the cross line which marks the end of the thirtieth inch space as well as the square cut end of the fifth six-inch section; the numeral 20 designates the cross line which marks the end of the thirty-sixth inch section as well as the square cut end of the sixth six-inch section; the reference character 21 designates the cross line which marks the end of the forty-second inch space as well as the square cut end of the seventh six-inch section; and the reference character 22 designates the cross line which marks the end of the forty-eighth inch space as well as the square cut end of the last section of the ruler illustrated in Figure 1.

It will be apparent from the above that when the ruler is open to the position illustrated in Figure 3, the distance from the end 23 of the ruler to the cross line 16 will be exactly 12", also the distance from the cross line 16 to the cross line 18 will be exactly 12", and similarly the distance between the cross lines 18 and 20 and the cross lines 20 and 22 will be exactly 12". Thus should the ruler be broken at an intermediate section, such for example as at the point indicated at 24 in Figure 1 of the drawing, it will only be necessary to remove the remaining portion of the next to the last section 11, thereby leaving a ruler which will run from point 23 to point 20, which ruler will still be made up of equal 6" sections and will be as capable of efficient use as the original ruler, only that the same will be one foot shorter in length.

It will be readily understood that should the said ruler be injured or broken at a point indicated at 25 in Figure 1, the remaining portion of the said fifth section in which the break occurred may be readily removed, thereby leaving a complete two-foot rule, which will still be efficient in operation. Thus it will be noted that I have provided a folding rule made up of sections which are so arranged that the same may be broken off intermediate the ends thereof without destroying the utility and efficiency of the rule.

In order to facilitate in the reading of measurements made with my improved rule, I have provided in addition to the markings usually present in an ordinary ruler, the marking 26 as shown in Figure 1, which markings start with the numeral 1 at the end of the first inch space on the third section of my rule, said markings being numbered from one to twelve on the inch spaces provided on the third and fourth sections of my rule. Similarly, the fifth and sixth sections are marked from one to twelve inclusive, as well as the seventh and eighth sections marked from one to twelve inclusive. This it will be noted is provided in addition to the usual markings numbered from one to forty-eight, which is common in the ordinary rule.

I have found that the provision of these additional markings or numbers greatly facilitates in the use of my improved ruler. To prevent confusion, the one to twelve markings may be made somewhat larger and on one side of the cross lines 13, whereas the one to forty-eight markings may be made smaller and on the other side of said cross lines 13, as more clearly illu-

trated in Figure 2 of the drawing. The reverse side of the ruler is marked the same way, only that the said markings are started from the end 22 of the ruler instead of the end 23 as illustrated in Figure 1.

In providing the square cut ends 15, 16, 17 and so on, for each of the sections of said rule, the use of the rule in taking measurements of flat objects may be greatly facilitated by using the same in the manner illustrated in Figure 3 of the drawing. In this figure there is shown a flat surface, such as the top of a table 27 or the like, upon which may be placed the rule 10 in unfolded position one of the square ends 16 for example resting against the side edge of said table 27, in which position it will be comparatively simple to measure or to lay off the desired distance on said table 27, since the markings from this point 16 begin with one as indicated at 26 in Figure 1.

It will also be noted that should it be desired to lay off on a flat surface such as the table 27 illustrated in the drawing, distances of six or twelve inch lengths, it will only be necessary to move said rule to the right as viewed in Figure 3 in successive steps with the square end 16, 17, and so on, striking against the edge of said table and a mark placed adjacent the end of the rule every time one of said square ends is disposed against said side edge of the table. This simple operation will result in the laying out of equal six-inch spaces on said table or on a sheet of paper disposed thereon.

From the above description and operation of my improved ruler it will be obvious that I have provided a simple construction of folding ruler, the life of which will be prolonged and the usefulness thereof extended for a period much longer than that of the ruler now in use because of the fact that the efficiency and utility of the same is not destroyed by injury to or breakage of a portion thereof.

It is believed that my invention, its mode of construction and many of its advantages should be readily understood from the foregoing without further description, and should also be manifest that while a preferred embodiment of the invention has been shown and described for illustrative purposes, the structural details are, nevertheless, capable of wide variation within the purview of my invention as defined in the appended claim.

Having described my invention, what I claim and desire to secure by Letters Patent of the United States is:—

A folding ruler of the character described comprising a plurality of sections, each of which is divided by transverse lines into rectangular spaces and successively increasing distances from a common zero point at the end of one section of the ruler, said transverse lines being numbered from 1 to 6 on the first of said sections and from 6 to 12 on the second of said sections, and again from 1 to 6 on the third of said sections and from 6 to 12 on the fourth of said sections, said numbering being repeated in the above mentioned manner to the end of the rule, and said lines beginning with the third of said sections being numbered in addition to the above numbers with numbers indicating the distance of said lines from the common zero point.

GUSTAV J. T. NEUBERG.
